MINERAL CONCENTRATOR

Robert Smith, Ajo, Ariz., assignor to Robert S. Davis, Rowood, Ariz.

Application October 24, 1936, Serial No. 107,427

9 Claims. (Cl. 209—466)

This invention relates generally to the art of handling ore bearing materials to recover the values therein by utilizing the dry method of separation.

5 An object of the invention is to provide a mineral concentrator which is structurally characterized in a manner to enable all small fine values as well as the coarser values to be profitably recovered on a mass tonnage or yardage basis by an economical expenditure of power.

10 Another object of the invention is to provide a concentrator embodying primary and secondary concentrating compartments to which the material is successively delivered and subjected 15 both to mechanical agitation and the separating action of controlled streams of air in such manner as to insure the maximum recovery of all values, notwithstanding the fineness thereof.

15 A further object of this invention is to provide 20 a mineral concentrator wherein the concentrating unit to which the ore bearing material is delivered in a ground or pulverized state for action therein by air, is mounted for agitation about a vertical axis in a new and novel manner 25 to greatly facilitate the separation process in conjunction with the action of air upon the material, all to the end of effecting maximum recovery of values.

With these and other objects in view, the invention consists in the combinations, arrangements and functional relationships of elements as set forth in the following specification and particularly pointed out in the appended claims.

In the accompanying drawings,

35 Figure 1 is a view showing partly in side elevation and partly in vertical central section, the mineral concentrator embodying this invention;

Figure 2 is a horizontal sectional view on a reduced scale, taken on the line 2—2 of Figure 1, 40 and looking in the direction of the arrows;

Figure 3 is a vertical sectional view taken on the line 3—3 of Figure 2 and looking in the direction of the arrows;

Figure 4 is a plan view of the concentrating unit;

Figure 5 is an enlarged fragmentary sectional view taken on the line 5—5 of Figure 4;

Figure 6 is a detail sectional view taken on the line 6—6 of Figure 1;

50 Figure 7 is a perspective view of an adjustable control member for the secondary concentrating compartment.

Referring specifically to the drawings, this invention in its present embodiment comprises a suitable base 10 vertically supporting a casing

11 in the general form of a cone frustum, the upper edge of which is reinforced by an L-shaped ring 12. Yieldingly or resiliently supported from the casing and within the latter is a concentrating unit C. Above the concentrating unit is a 5 delivery hopper H which is circular in plan and is rigidly supported from the casing by a plurality of struts 13 disposed at circumferentially spaced intervals. The hopper H is formed by a shallow inverted conical delivery table 13a on which the 10 ore bearing material in a dry and ground or pulverized state is delivered so as to gravitate therefrom through an axially disposed discharge opening 14 into the concentrating unit.

The concentrating unit C comprises a circular 15 head 15 having a relatively large central opening 16, the wall of which flares upwardly and is spanned by a relatively fine screen 17 preferably of from 80 to 200 mesh, which, in practice, can be supported and protected on opposite sides by 20 heavier screens, to provide a reticulated table onto which the ore bearing material is deposited around a deflector 18 of conical form supported axially in the opening 16 by a diametrically extending spider 19 secured at 20—20 to a depending collar 21 surrounding the opening 16. It is to be noted that the deflector 18 is threaded 25 mounted in the hub of the spider 19 so as to be vertically adjustable to vary the size of the discharge opening 14 in order to control the feed of 30 material from the hopper H.

Also secured to the collar 21 to depend therefrom is an upwardly flaring tubular body 22 having open ends and composed of sections 23 and 24 secured together by bolts 25 which clamp 35 a solid partition 26 between the sections to divide the body transversely intermediate its ends into chambers 27 and 28. The lower open end of the section 24 is closed by a removable cover plate 40 in the form of a relatively shallow cup 29.

The yielding or resilient support of the concentrating unit C as above generally characterized structurally is provided by a plurality of cables 30, four in number in the present instance, and anchored to the head 15 at equally spaced points circumferentially to extend radially over pulleys 31 swiveled at 32 to the casing 11. From the pulleys the cables extend downwardly for connection to draw bars 33 slidably 50 mounted in lugs 34 on the casing 11. Springs 35 are confined between the lugs 34 and nuts 36 threaded on the bars for co-action therewith in maintaining the cables under sufficient tension to yieldingly support the head in a central posi- 55

tion against lateral displacement relative to the hopper H.

At its lower end the concentrating unit is mounted on the base 10 for agitation by the following mechanism. Journalized vertically in bearings 31-31 is a vertical shaft 38 having fixed thereto a pulley 39, which, through belt and pulley connections 40, 41 and 42 from the shaft of a blower 43, is adapted to be driven, a suitable friction disk clutch F being also provided to control the operation and speed. Mounted in a radial recess 44 of the pulley 39 is a block 45 from which projects vertically a stud 46 having on its upper end a ball 47 confined between anti-friction bearings 48-48 mounted in a depending tubular extension 49 of the cup 29, so as to provide a universal connection between the lower end of the concentrating unit and the driving mechanism. The block 45 can be adjusted to vary the eccentricity of the stud with respect to the shaft 38 so as to correspondingly vary the magnitude of the continuous tilting motion in the circular path about a vertical axis imparted to the unit in accordance with the requirements of the material being concentrated.

Cap screws 50 threaded into the pulley 39 and passing through slots 51 in the block 45 enable the stud to be rigidly secured in any desired position of eccentric adjustment.

The blower 43 and a power plant 52 for driving same are supported on the base 10; and air from the blower is adapted to be delivered through a lateral inlet 43a to the upper chamber 27 so as to discharge upwardly therefrom through the screen 17 into an upper and primary concentrating compartment P provided by the head 15 above the screen, and in which concentration is effected in two stages. Part of the air is adapted to flow downwardly through a pipe 53 into the chamber 54 formed by the cup 29 below a relatively fine screen 55 through which the air is then forced into the chamber 28 which constitutes a lower and secondary concentrating compartment S. The pipe 53 is supported axially in the body 22 by being secured at its upper end to the partition 26 in surrounding relation to a central opening 56 therethrough, and by being secured at its lower end to the screen 55 in surrounding relation to an opening 57 therethrough, all as clearly shown in Figure 1. Mounted in the pipe 53 is a manually operable valve 58 by which the flow of air to the concentrating compartment S is controlled.

The section 24 of the body 22 is provided with a lateral outlet 59 for the discharge of air, sand and dust particles from the concentrator. A flexible connection 60 between the inlet 43a and the blower 43 permits unrestricted agitation of the blower; and flexible rings 61 and 62 between the casing 11 and unit C, and between the flexible discharge pipe 63 and the casing respectively, co-act with the casing and with a hood 64 enclosing the blower and power plant, to protect all mechanism from dust and grit particles.

Part of that air flowing upwardly in the chamber 27 passes through V-shaped recesses 65 formed in the walls of the opening 16 immediately below the screen 17. This air can pass through a vertical annular screen 66 seating in a groove 67 and spanning the recesses. From the screen the air discharges into an annular pocket 68 covered by a relatively coarse screen 69 through which the air finally discharges beneath the hopper around the head. Concentrates col-

lecting in the pocket 68 can discharge therefrom through flexible tubes 69a under the control of valves 70 to the lowest level of the secondary concentrating compartment S; and high grade concentrates can be removed from the secondary concentrating compartment through an outlet 71 under the control of a valve 72, all as clearly shown in Figure 3. As the lower portion of the compartment S is subject to wear, it is provided with a removable ring 73 having its upper edge recessed various depths as indicated at 74, 75 and 76 in Figure 7. By circumferentially adjusting the ring to dispose one portion or another thereof to the outlet 59, lips of different heights will be provided to increase or decrease the portion of concentrates being worked. It is to be noted that the lower edge of the ring 73 is provided with openings 77 in order to provide communication between the compartment S and the outlet 71 in all positions of adjustment of the ring.

Another part of the air flowing upwardly in the chamber 27 passes through a series of radial ducts 78 in the head 15 communicating at their inner ends with the opening 16 below the screen 17, and spanned at their outer ends by an annular screen 79 of a construction and mesh similar to that of the screen 17 and also constituting a reticulated table. The outer edge of this screen seats in a groove 80 in the head; and its inner edge is confined against displacement by a removable wear ring 81 which, together with a second wear ring 82 forms a riffle 83 above the pocket 68 to trap values so that such fine values and black sand can gravitate into the tubes 69a.

Removable wear rings 84 and 85 form a final riffle 86 above the outer marginal portion of the screen 79 to prevent loss of values which are freed from gangue material after passing over the riffle 83. Openings 87 and 88 closed by plugs 89 and 90, respectively, are provided at suitable locations for cleanup purposes. Attached to the hopper H and extending therebeneath at a suitable distance above the head 15 is a disk 91 of flexible sheet material, such as cotton or woolen fabric which functions to check or retard flecky and light ore particles in order to permit such particles by a change of position to one edge-wise of the air current, to gravitate to a lower lever and be recovered.

The operation of the invention is as follows: Let it be assumed that the blower 43 is in operation to supply air to the concentrating unit C and that the latter is being agitated. Ore bearing material in a dry and pulverized or ground state is deposited in the hopper H and gravitates therefrom onto the screen 17 around the deflector 18. Due to the character of the agitating or tilting motion of the concentrating unit about a vertical axis which is axially related to both concentrating compartments P and S, the deposited material travels over and above the screen 17 in a slow circular motion outwardly from the center of the compartment P, during which time the material is subjected to the separating action of the upwardly moving air current traversing the screen 17. The material is, as a result of this combined mechanical and fluid agitation, subjected to a milling, grinding and polishing action, with the pulverization and elimination of any clayey substances containing or adhering to values. By virtue of the milling action of the concentrator and the boiling action effected by the air current, the values, black sand and all heavier particles, are permitted to seek the lowest levels, the dust being slightly 75

raised and carried off to atmosphere by the air, and other gravel and gangue material being finally discharged from the head 15 at the periphery thereof, which method is a distinct advantage and improvement over prior machines which are fed at a higher elevation and discharged at a lower one.

The concentrates consisting of fine values and sand in seeking the lowest level are deposited in the annular pocket 68 through the screen 69 and are subjected to additional concentrating action by air streams from the main upward current, in order to prevent fine particles of gangue from sifting into the pocket 68. These streams of air pass through the recesses 65 and the vertical screen 66, which latter functions to prevent the concentrates from gravitating into the chamber 27.

Any material containing values which passes the riffle 83 continues its outwardly and upwardly circular motion over the screen 79 and is subjected to further concentrating and milling action by the upwardly moving air streams traversing the ducts 78, the concentrates being checked by the riffle 86, and clean-up being effected through the opening 87 upon removal of the plug 89.

The concentrates deposited in the pocket 68 gravitate through the tubes 69 in accordance with the adjustment of the respective valves 10 and enter the concentrating compartment S on the screen 55. In this compartment, the concentrates are subjected to a more violent mechanical agitation by the eccentric driving mechanism as the greatest tilting or swinging motion of the unit in a circular path about a vertical axis is present at the universal operative connection between the driving mechanism and the concentrating unit below the compartment S. In addition to this violent mechanical agitation the concentrates are subjected to the action of the upwardly moving air blast from beneath the screen 55, all to the end that any fine values still adhering to the black sand or to lighter or heavier particles will be freed therefrom.

It is to be noted that the ring 73 which forms the wall of the compartment S is in the form of a cone frustum so that the top of the compartment is smaller in area than the bottom at which the concentrates enter the compartment. This form of the compartment tends to prevent the values and the particles containing values from ascending. Gangue particles which spill over the ring flow by gravity from the concentrator through the flexible pipe 63. High grade concentrates can be removed at intervals through the outlet 71 when the valve 72 is opened, and it will be manifest that by virtue of the aforesaid structure and mode of operation frequent delays and cleanups are eliminated, and a higher grade concentrate obtained with a minimum loss in recovery.

I claim:

1. A mineral concentrator having a concentrating head provided with an axial air passage therethrough and an annular pocket for concentrates, surrounding said passage; a reticulated bottom spanning said passage and onto which ore bearing material is adapted to be deposited at a central location; means for agitating the head to effect motion of the material outwardly towards said pocket; means for subjecting material to an air blast through said passage so as to aid the agitating means in separating gangue from the material, an annular riffle correlated with said pocket to check upward movement of concen-

trates from the pocket; and means providing communication between the air passage and pocket below said reticulated bottom for the admission of air blasts from the passage in order to prevent fine particles of gangue from sifting into said pocket. 5

2. A mineral concentrator having a concentrating head provided with an axial air passage therethrough and an annular pocket for concentrates surrounding said passage; a reticulated bottom spanning said passage and onto which ore bearing material is adapted to be deposited at a central location; means for agitating the head to effect motion of the material outwardly towards said pocket; means for subjecting the material to an air blast through said passage so as to aid the agitating means in separating gangue from the material; an annular riffle correlated with said pocket to check upward movement of concentrates from the pocket; relatively coarse reticulated material spanning said pocket and through which the concentrates can gravitate into the pocket; means providing communication between the air passage and pocket below said reticulated bottom for the admission of air blasts from the passage in order to prevent fine particles of gangue from sifting into said pocket, the head having ducts the inner ends of which open to said air passage, and the outer ends of which open upwardly at locations outwardly of said riffle; reticulated material spanning the outer ends of said ducts and onto which material spilling over said riffle is adapted to deposit and be subjected to the action of air blasts from said ducts; and a second annular riffle correlated with the last mentioned reticulated material to check the ascent of concentrates from the latter. 20 25 30 35

3. A mineral concentrator comprising a concentrating unit having upper and lower concentrating compartments; means defining reticulated bottoms for the respective compartments; means from which ore bearing material is adapted to discharge onto the central portion of said bottom for the upper compartment; means for agitating said unit by continuously tilting same in a circular path about a vertical axis to cause material deposited on said one of the bottoms to travel in a circular path outwardly thereof; means for directing air blasts through the bottoms to coact with the agitation of the unit in removing gangue from the material as it traverses said one of the bottoms; means correlated with said one of the bottoms, into which concentrates from the material are caused to be deposited; and means for conducting such concentrates to the bottom of the lower concentrating compartment for higher concentration by the combined mechanical agitation and action of the air blast. 40 45 50 55

4. A mineral concentrator comprising a concentrating unit having upper and lower concentrating compartments; means defining reticulated bottoms for the respective compartments; means from which ore bearing material is adapted to discharge onto the central portion of said bottom for the upper compartment; means for agitating said unit by continuously tilting same in a circular path about a vertical axis to cause material deposited on said one of the bottoms to travel in a circular path outwardly thereof; means for directing air blasts through the bottoms to coact with the agitation of the unit in removing gangue from the material as it traverses said one of the bottoms; means correlated with said one of the bottoms, into which concentrates from the material are caused to be deposited; means for conducting said concentrates to the bottom of the 60 65 70 75

- lower concentrating compartment for higher concentration by the combined mechanical agitation and action of the air blast; valved means for regulating the flow of concentrates to the lower concentrating compartment; and valved means for regulating the flow of air to the concentrates being worked in the lower concentrating compartment.
5. A mineral concentrator comprising a concentrating unit having upper and lower concentrating compartments; means defining reticulated bottoms for the respective compartments; means from which ore bearing material is adapted to discharge onto the central portion of said bottom for the upper compartment; means for 10 yieldingly supporting the upper portion of said unit against lateral displacement; means for agitating said unit from the lower portion thereof by continuously tilting same in a circular path about a vertical axis to cause material deposited 15 on said one of the bottoms to travel in a circular path outwardly thereof; means for directing air blasts through the bottoms to co-act with the agitation of the unit in removing gangue from the material as it traverses said one of the bottoms; 20 means correlated with said one of the bottoms into which concentrates from the material are caused to be deposited; and means for conducting such concentrates onto said bottom of the lower concentrating compartment for higher 25 concentration by the action of the air blast and the more violent agitation of the unit at the lower portion thereof.
6. A mineral concentrator of the character embodied in claim 5, wherein said agitating means 30 includes an eccentric driving member; and a universal connection between said member and unit.
7. A mineral concentrator of the character embodied in claim 5, including an outlet in said

lower compartment for the removal of high grade concentrates; and a valve controlling the outlet.

8. A mineral concentrator comprising a concentrating unit having superposed concentrating compartments; means for delivering ore bearing 5 material to the upper compartment; means for conducting concentrates from the upper compartment to the lower compartment by gravity following initial concentration of the material in the upper compartment; means for agitating 10 the unit by effecting continuous tilting thereof in a circular path about a vertical axis so as to cause the material to traverse the respective compartments; and means for subjecting the material to the action of air blasts as the material 15 traverses the compartments, whereby to remove gangue from the material.

9. A mineral concentrator comprising a concentrating unit having superposed concentrating compartments; means for delivering ore bearing 20 material to the upper compartment; means for conducting concentrates from the upper compartment to the lower compartment by gravity following initial concentration of the material in the upper compartment; means for agitating the unit 25 by effecting continuous tilting thereof in a circular path about a vertical axis so as to cause the material to traverse the respective compartments; means for subjecting the material to the action of air blasts as the material traverses the 30 compartments, whereby to remove gangue from the material; means by which the flow of concentrates from the upper compartment to the lower compartment can be varied; and means by 35 which the volume of air delivered to the lower compartment can be varied.

ROBERT SMITH.
